CLAIM

The ornamental design for a shoe, as shown and described.

DESCRIPTION

FIG. 1 is a first side, perspective view of a shoe showing my design;

FIG. 2 is a plan view thereof;

FIG. 3 is a second side, perspective view thereof; and,

FIG. 4 is a front, perspective view thereof.

The even-length broken lines are directed to environment, represent unclaimed subject matter, and form no part of the claimed design. The long and short broken lines form an unclaimed boundary around the claimed subject matter and form no part of the claim.
